United States Patent

Des. 236,153
Patented July 29, 1975

236,153

CLAMP

Derek Hogg and John Fairburn Askam, Sutton Coldfield,
England, and Roger Anthony Wilson, Wrexham, Wales,
assignors to Dunlop Limited

Filed Nov. 6, 1972, Ser. No. 303,800

Claims priority, application Great Britain May 11, 1972

Term of patent 14 years

Int. Cl. D15—99

U.S. Cl. D54—13 A

FIG. 2

FIG. 1

FIG. 4

FIG. 3

FIG. 1 is a perspective view taken from the left and front of a clamp showing our new design;

FIG. 2 is a perspective view thereof taken from the right and front;

FIG. 3 is a perspective view thereof taken from the left and front with an element in an alternate position; and

FIG. 4 is a perspective view of the clamp of FIGS. 1 and 2 taken from the front.

We claim:

The ornamental design for a clamp, as shown and described.
